UNITED STATES PATENT OFFICE.

CHARLES C. SPREEN, OF DETROIT, MICHIGAN, ASSIGNOR TO ELECTRIC REFRIGERATION CORPORATION, OF DETROIT, MICHIGAN, A CORPORATION OF MICHIGAN.

REFRIGERATION.

Application filed January 7, 1927. Serial No. 159,626.

My invention relates to mechanical refrigeration, and particularly to adjustable means for supporting the expander from the sides of the door opening of a refrigerator cabinet compartment, and the principal object of my invention is to provide new and improved means of this type. In the drawings accompanying this specification and forming a part of this application I have shown, for purposes of illustration, two forms which my invention may assume, and in these drawings:

Figure 1 is a sectional elevation showing one embodiment which my invention may assume.

Figure 2 is a vertical section on the line 2—2 of Figure 1, while

Figure 3 is a similar vertical section showing a variation this embodiment of my invention may assume.

The embodiment of my invention shown in Figures 1 and 2 comprises a refrigerator cabinet 11 having a refrigerating compartment 12 provided with a door opening 13.

An expander 14 is supported in the compartment 12 by means of two pairs of spaced bars 15 and 16 which are attached in pairs to opposite sides of the door opening 13 by screws, or the like, 17. The bars 15 and 16 of each pair extend into the compartment 12 in a converging direction and are provided at their free ends with pairs of spaced apertures 18. One end of the expander 13 carries attaching means herein shown as a collar 19 which is provided with lugs 20 having formed therein screw threaded spaced apertures adapted to engage with screws 21 which pass through a selected pair of apertures 18 in the end of each bar 15 or 16.

After the expander 14 has been properly adjusted in spaced relation to the walls of the compartment 12, the bars 15 and 16 are fixedly secured in position by additional screws 22 driven in the sides of the opening 13.

In the embodiment of my invention shown in Figure 3 the brine tank 22 is supported in the compartment 24 of the refrigerator cabinet 25 by means of pairs of bars 26 and 27 which differ from the bars 15 and 16 in that they are made of sections which are adjustable in a lengthwise direction; thus providing for a greater range of adjustability in mounting the brine tank 22.

The feature of adjustability herein dis-

closed obviously permits use of a single type of support in compartments and with expanders of different size.

From the above disclosure it will be obvious to those skilled in the art that I have provided new and improved adjustable means for mounting an expander in the refrigerating compartment of a refrigerator cabinet.

At the same time it will also be obvious to those skilled in the art that the embodiment of my invention herein shown and described may be variously changed without departing from the spirit of my invention or sacrificing the advantages thereof, and it therefore will be understood that the disclosure herein is illustrative only, and that my invention is not limited thereto.

I claim:

1. In combination with a mechanical refrigerator, comprising a cabinet provided with a compartment, with an opening through one wall for affording access to said compartment, and with a door for closing said opening: of means for supporting an expander within said compartment, comprising attaching means to opposed sides of said cabinet adjacent the opening.

2. In combination with a mechanical refrigerator, comprising a cabinet provided with a compartment, with an opening through one wall for affording access to said compartment, and with a door for closing said opening: of means for supporting an expander within said compartment, comprising attaching means carried by said expander, and pairs of spaced bars connecting said attaching means to opposed sides of said cabinet adjacent the opening.

3. In combination with a mechanical refrigerator, comprising a cabinet provided with a compartment, with an opening through one wall for affording access to said compartment, and with a door for closing said opening: of means for supporting an expander within said compartment, comprising attaching means carried by said expander, and pairs of spaced bars adjustably connecting said attaching means to opposed sides of said cabinet adjacent the opening.

4. In combination with a mechanical refrigerator, comprising a cabinet provided with a compartment, with an opening through one wall for affording access to said compartment, and with a door for closing said opening: of means for supporting an ex-

2
pander within said compartment comprising attaching means carried by said expander, and bars, adjustable on said attaching means, adjustably connecting said attaching means 5 to opposed sides of said cabinet adjacent the opening.

5. In combination with a mechanical refrigerator, comprising a cabinet provided with a compartment, with an opening through 10 one wall for affording access to said compartment, and with a door for closing said opening: of means for supporting an expander within said compartment, comprising attaching means carried by said expander, and pairs of lengthwise adjustable bars 15 adjustably connecting said attaching means to opposed sides of said cabinet adjacent the opening.

6. In combination with a mechanical refrigerator, comprising a cabinet provided with a compartment, with an opening through 20 one wall for affording access to said compartment, and with a door for closing said opening: of means for supporting an expander within said compartment, comprising a collar disposed about said expander, and means connecting said collar to opposed 25 sides of said cabinet adjacent the opening.

7. In combination with a mechanical refrigerator, comprising a cabinet provided with a compartment, with an opening through 30 one wall for affording access to said compartment, and with a door for closing said opening: of means for supporting an expander within said compartment, comprising a collar disposed about said expander, and pairs of spaced bars connecting said 35 collar to opposed sides of said cabinet adjacent the opening.

40 8. In combination with a mechanical refrigerator, comprising a cabinet provided with a compartment, with an opening through one wall for affording access to said compartment, and with a door for closing said

opening: of means for supporting an expander within said compartment, comprising a collar disposed about said expander and pairs of spaced bars adjustably connecting said collar to opposed sides of said cabinet adjacent the opening.

50 9. In combination with a mechanical refrigerator, comprising a cabinet provided with a compartment, with an opening through one wall for affording access to said compartment, and with a door for closing said 55 opening: of means for supporting an expander within said compartment, comprising a collar disposed about said expander, and bars, adjustable on said collar, adjustably connecting said collar to opposed sides 60 of said cabinet adjacent the opening.

10. In combination with a mechanical refrigerator, comprising a cabinet provided with a compartment, with an opening through 65 one wall for affording access to said compartment, and with a door for closing said opening: of means for supporting an expander within said compartment, comprising a collar disposed about said expander, and pairs of lengthwise adjustable bars 70 adjustably connecting said collar to opposed sides of said cabinet adjacent the opening.

11. In combination with a mechanical refrigerator, comprising a cabinet provided with a compartment, with an opening through 75 one wall for affording access to said compartment, and with a door for closing said opening: of means for supporting an expander within said compartment, comprising attaching means carried by said expander, and pairs of lengthwise adjustable spaced bars 80 adjustably connected to said attaching means adjustably connecting said attaching means to opposed sides of said cabinet adjacent the opening.

85 In testimony whereof I hereunto affix my signature.

CHARLES C. SPREEN.
